EXPANDER ROLL

John D. Robertson, Taunton, Mass.

Application February 21, 1945, Serial No. 579,122

3 Claims. (Cl. 26—63)

This invention relates to improvements in expander rolls for flexible sheet materials, and more particularly to such rolls having curved or bowed extent between their ends and whose principal utility is for stretching fabric weft-wise and for removing wrinkles from fabric webs in the course of their travel to or from any of various textile machines or frames.

Expander rolls of the general type to which the invention relates ordinarily have a surface of rubber or other resiliently flexible material engaged over a series of roll sections which are rotatably mounted on a curved axially extending shaft held at its opposite ends in clamps customarily mounted on the frame of the particular machine with which the expander roll is associated. The web of cloth comes to the roll at the inner side of its bowed extent and leaves the roll at its outer side, the rubber surface element of the roll having to expand and contract as the roll rotates to accommodate the enclosed roll sections. The web passing around the roll becomes spread or expanded laterally thereby to remove wrinkles and to get the web into fully extended condition.

However, the prior expander rolls of this general type have not been entirely satisfactory and have been quite unsuitable for handling delicate and sheer fabrics. Heretofore the rolls introduced heavy tensional strains on the web due to relatively large resistance to turning in response to draft of the web trained thereover.

The tensional strains imposed warpwise of the fabric have to a large extent counteracted the desired spreading effect of the roll weftwise of the fabric with the result that relatively little increase in the width of the fabric has been attainable with the prior curved expander rolls. Also, the mentioned warpwise tensional strains have been so severe as sometimes to damage even the more stable and rugged fabrics. Sheer and delicate fabrics could not safely be subjected to the action of the prior rolls in any event. Also it has been a problem to hold the ends of the prior roll shafts against the considerable stresses acting to loosen the end clamps.

All prior curved expander rolls, so far as I am aware, have required a positive inter-locking engagement between the adjacent roll sections to insure that no one or more sections would be held against rotation by accumulations of foreign matter or corrosion at bearing regions. Customarily, the roll sections have been provided at their ends with coacting clutch teeth or the like which involve substantial amounts of frictional rubbing due to the different planes of rotation of the interlocked roll sections. Also the abrasive action at the clutch teeth caused substantial quantities of abraded particles to get into the bearing bushings

of the roll sections to further increase frictional resistance to rotation of the sections.

Various attempts have been made heretofore to reduce friction in curved expander rolls so that a roll as an entirety might be more sensitive to draft of a web of fabric trained thereover. The seemingly obvious remedy of mounting the roll sections on ball bearings was among the things tried and found impractical and unsuccessful, due to rapid gumming of the balls which in a short time prevented relative rotation of the ball races. As soon as this condition occurred in one roll section, any further rotation of the roll as a whole about the shaft involved rotation of both inner and outer ball races of the stuck unit, which scored the shaft and resulted in hastening clogging and sticking of adjacent ball units until the roll ultimately became entirely unfit for service.

It is among the objects of the invention to provide an expander roll which can serve efficiently and effectively for expanding or spreading flexible sheet materials generally including delicate and sheer textile fabrics, and without imposing on the sheets or webs any damaging amount of warpwise tensional strain. I provide an improved curved or bowed roll construction having roll sections which are relatively freely rotatable on their support shaft, and having a resiliently flexible surface tube of rubber or the like which more readily and smoothly can execute requisite expansions and contractions as compared with prior rolls, and which in consequence can have a substantially prolonged useful life because of reduced abrasive action of the cloth on the rubber surface.

Another object is to provide an expander roll structure comprising a series of spaced roll sections each rotatable on a separate anti-friction bearing unit and all of the sections rotatably supported on a curved supporting shaft and covered by a resiliently flexible surface tube of rubber or the like.

A further object is to provide an expander roll having a series of roll sections rotatably spaced apart on a non-round longitudinally curved rigid supporting shaft.

Still another object is to provide a longitudinally curved expander roll having a supporting shaft with straight end sections generally tangent to the adjacent curved portions, and a universally adjustable clamp securing the end sections of shaft with the curved extent of the shaft in any of various planes.

Yet another object is to provide a longitudinally curved expander roll and end clamps for the opposite ends of the roll, each clamp having universally adjustable jaws for receiving an end of said roll disposed in any of a variety of angular positions.

It is, moreover, my purpose and object generally to improve the structure, effectiveness and efficiency of longitudinally curved expander rolls.

In the accompanying drawing:

Figure 1 is an elevational view of a mounted longitudinally curved expander roll embodying features of my invention, a fragment of the outer covering of the roll being broken away to show the interior sectional roll structure;

Figure 2 is a fragmentary cross-sectional view of one end portion of the roll of Figure 1, on a larger scale;

Figure 3 is a cross-sectional view on line 3—3 of Figure 2;

Figure 4 is an end elevation of one of the end clamps of Figure 1, the roller shaft being shown in cross-section engaged in the clamp; and

Figure 5 is a cross-sectional view on line 5—5 of Figure 4.

Referring to the drawing, my improved expander roll comprises a rigid bowed shaft 10 which is non-round in cross-section, the particular shaft herein illustrated having hexagonal cross-section and having the straight end portions 12, 14 rigidly and securely fixed in the similar end clamps 18, 20. Each clamp 16 has a pair of jaws 18, 20 which are adjustable universally in a bearing member 22 so that the straight end portions 12 of the shaft can be generally tangent to the adjacent curved portions and the shaft may be set with its bowed extent in any desired plane and securely held by the clamps with a minimum of strain on the clamps when the roll sections, to be described, are rotated on the bowed portion of shaft 10. The bearing members 22 may be mounted on any suitable support which ordinarily will be a frame part 23 of a machine.

The mentioned universal adjustment of a clamp 16 is attained by means of exterior spherical surfaces 24, 26 on jaws 18, 20 respectively, the spherical surfaces 24, 26 seating in an interior annular groove 28 in bearing member 22 which groove has a bearing surface complementary to the spherical surfaces of the jaws seating therein. Jaw 18 has a deep notch 30 therein whose bottom is shaped to seat two adjacent flats of the hexagonal shaft 10. The other jaw 20 is narrower and fits into the notch 30 in jaw 18, its clamping face 32 being shaped to seat two adjacent flats of shaft 10 on the opposite side of the shaft from the flats seated in jaw 18.

It is a feature of importance that the annular seat for the jaws in bearing member 22 definitely limits the extent of possible opening of the jaws to only slightly more than enough to permit the end of shaft 10 to be inserted between them, and the jaws can adjust themselves within bearing member 22, much in the manner of a ball in a socket, so that the jaws will be in position for flatwise clamping of flats of the shaft regardless of the angle of entry of the shaft into the clamp. When the clamp is properly adjusted with an end of shaft 10 between its jaws, a screw 34 in bearing member 22, or preferably two such screws as illustrated, may be screwed inward to force jaw 18 in direction out of its annular seat 28 into clamping engagement with shaft 10, jaw 20 being meanwhile forced tightly against its seat in groove 28, whereby the clamp is made rigid and secure in bearing member 22 with an end of shaft 10 firmly held between the jaws 18, 20. The relatively small movement of the jaws enables the said tightening of the clamp to be effected with-

out jaw 18 being forced out of retained relation to annular groove 28.

Figs. 1 and 2 illustrate my improved construction of the curved roll which is rotatable on the bowed shaft 10. Referring more particularly to Fig. 2, a plurality of cylindrical tubular roll sections 36, 38 are enclosed within a resiliently flexible tube 40 of rubber or other suitable material. A roll section 36 is at each end of the roll and has an end cap 42 secured thereto as by the screws 44. Each end cap 42 has an axial hole 46 in its end wall for passage of shaft 10 and, preferably, the periphery of each end cap is grooved as at 48 for reception of a lock-ring 50 of stiffly resilient wire which engages in the grooves of the heads of screws 44, locking them against becoming loose, the ends of the wire ring being bent as at 52 for engaging in a hole 54 in the end cap as best seen in Fig. 3.

The resiliently flexible tube 40 is stretched somewhat in getting it over the roll sections 36, 38 so that it strongly grips the sections. Its opposite ends are butted against the ends of the flanges of the end caps 42, the tube preferably being under longitudinal compression between the end caps. If desired, the end portions of tube 40 may be mechanically secured to the end sections 36 in any well known manner, or they may be cemented to the end sections at their surfaces of cleavage. However, the resilient grip of the tube on the end sections as on the intervening sections, ordinarily will be found sufficient without additional securement of the tube to the sections.

The composite roll as a unit is held against longitudinal movement on shaft 10 by the retaining rings 56, one secured to shaft 10 within each end cap 42, as by the set screws 58 which, preferably, are spotted into the shaft 10.

It is a feature of my invention that the roll sections 36, 38 can be spaced apart within the surface tube 40 with no inter-locking drive connection between adjacent sections, and with tube 40 bridging the spaces between roll sections at their peripheries. This is possible, according to the invention, by providing a separate ball bearing unit for each of the roll sections 36, 38, and by positively keying the inner ball race 60 of each unit to the shaft 10 with continuity of endwise compression of the inner ball races 60 from one retaining ring 56 on shaft 10 to the other. Conveniently and practically the shaft 10 will be non-round in cross-section, as herein illustrated, and the inner ball race 60 of each ball bearing unit will have an axial non-round hole 61 therethrough generally of the same cross-sectional shape as the shaft but slightly larger than the shaft so that an inner race 60 having an axially straight hole 61 therethrough may be slipped or forced onto the curved shaft 10 and be non-rotatable thereon. The outer ball race 62 of each ball bearing unit may be sectional as shown and is held in co-acting relation to the inner race 60 by a casing 64 whose periphery fits snugly within a roll section 36, 38, so that the casing 64 and its roll section rotate in unison. The balls 66 are seated between the two races 60, 62.

The mentioned spaced relation of roll sections is attained and maintained by the spacing sleeves 68, one between each adjacent pair of the ball bearing units. Sleeves 68 fit loosely over shaft 10 and engage the ends of inner races 60, and the endmost inner races 60 engage the retaining rings 56 which are fixed on the shaft, whereby the mentioned continuity of endwise compres-

sion of elements is attained between the retaining rings 56, with all of the inner races 60 and the spacing sleeves 68 stationary on shaft 10.

In the detail showing of Fig. 2, it will be seen that the roll sections 36, 38 each has an interior annular shoulder 70 for seating the end of the casing 64 of a ball bearing unit. Also, in Fig. 2, the inner race of the ball bearing unit within the endmost roll section 36 is shown engaged against the retaining ring 56. The next adjacent ball bearing unit, in the roll section 38, is held spaced from the endmost unit by one of the cylindrical spacing sleeves 68 which is loose on shaft 10. Similarly, the ball bearing units in all other roll sections 38 are spaced apart throughout the extent of the roll by spacing sleeves 68 engaged one between adjacent inner ball races 60.

Preferably, the interior shoulders 10 of roll sections 36, 38 on one side of the mid-point along the roll will face in one direction and on the other side of said mid-point will face in the opposite direction.

The generally curved contour of my improved composite roll involves rotation of the individual roll sections 36, 38 in planes which are slightly inclined with respect to each other. This is permissible with my disclosed structure due to the spacing apart of the roll sections as at 72. The opposite ends of each roll section are in parallel planes with the result that the space 72 between roll sections is wider at the convex side of the bow than on the concave side, which permits contraction of the rubber surfacing tube 40 on said concave side and causes stretching or expansion of the tube at said convex side of the bow, with the tube 40 bridging the spaces between roll sections to provide a continuous traction surface from one end to the other of the roll.

In use, a web of fabric or the like F comes to the roll at the concave side of its bowed extent at which side the length of the roll surface is materially less than at the convex side. The web is trained around the roll more or less, depending upon the degree of expansion of the web which is desired. Fig. 1 illustrates a web F having approximately a 180° engagement with the roll which provides a maximum of web expanding effect with the particular roll curvature as illustrated.

An important feature of the invention is the provision of an expander roll which is efficient and practical for handling all kinds of fabric webs including the sheer and delicate fabrics which heretofore could not safely be subjected to the action of prior curved expander rolls. My improved roll structure places a minimum of tensile strain warpwise on a fabric which is being expanded or spread laterally, and the resiliency flexible tubular roll surface more gently and easily executes its expansions and contractions under the influence of the roll sections, thereby increasing substantially the useful life of the surface tube as compared with prior rolls because of the reduced amount of abrasive action of the cloth on the rubber.

Also my improved end clamps co-act in reducing destructive strains on the clamps and on the roll to a minimum, while providing greater security of clamping and a superior degree of adjustability for setting the roll with its bowed extent in any selected plane. Also, my roll shaft may have its straight end portions 12 generally tangent to the adjacent curved portions which is important in that the inner ball races 60 and the spacing sleeves 68 readily may be slipped over the

straight end portions of the shaft and moved to their proper positions along the curved portions thereof.

I claim as my invention:

- 5 1. An expander roll for flexible sheet material, comprising a rigid longitudinally curved shaft having an angular cross-section, a series of anti-friction bearing units distributed in spaced relation along the shaft, each said unit including an inner part having an axial angular hole in which the shaft engages non-rotatably and an outer part which is freely rotatable on the inner part, a rigid tubular sleeve loose on the shaft between adjacent bearing units and maintaining the said spaced relation of the units, a series of cylindrical roll sections each mounted on a said outer part of a bearing unit for rotation therewith, at least some of said roll sections being canted slightly with respect to next adjacent roll sections, an end cap secured to each endmost roll section and having an axial hole for loose passage of said shaft, a retaining ring fixed on the shaft between the end wall of a said cap and the adjacent endmost bearing unit for maintaining said unit against outward longitudinal movement along the shaft, and a resiliently flexible tubular surface member covering all of the roll units and having its ends butted against said end caps.
- 10 2. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 15 3. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 20 4. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 25 5. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 30 6. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 35 7. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 40 8. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 45 9. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 50 10. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 55 11. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 60 12. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 65 13. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.
- 70 14. An expander roll for flexible sheet material, comprising a longitudinally curved shaft having an angular cross-section throughout and having straight end portions, multiple roll sections rotatable on the curved portion of the shaft, a flexible tube covering all of the roll sections and bridging spaces between the roll sections, interfitting means having interior angularly related surfaces loosely engaging angularly related surfaces of a said straight end portion of the shaft whereby the interfitting means and the shaft are maintained against relative rotation, said interfitting means having exterior generally spherical surfaces, a support having an interior generally spherical recess of fixed dimensions within which said interfitting means and the loosely engaged shaft are adjustable as a unit around the axis of the end portion of the shaft, and means for securing the interfitting means in selected adjusted positions within said recess of the support.

JOHN D. ROBERTSON.
